UNITED STATES PATENT OFFICE.

IGNATZ HERZOG AND RICHARD KOCH, OF NEW YORK, N. Y.

IMPROVEMENT IN LIDS FOR RETORTS.

Specification forming part of Letters Patent No. 159,671, dated February 9, 1875; application filed October 28, 1874.

To all whom it may concern:

Be it known that we, IGNATZ HERZOG and RICHARD KOCH, both of the city, county, and State of New York, have invented a certain new and useful Improvement in Closing the Mouths of Retorts, of which the following is a specification:

This invention is illustrated in the accompanying drawing, in which—

Figure 1 represents a front view when the lid is closed. Fig. 2 is a similar view when the lid is lowered ready to be swung open. Fig. 3 is a longitudinal vertical section.

Similar letters indicate corresponding parts.

This invention relates to an improvement on our patent for closing the mouths of retorts, which is numbered 148,455, and dated March 10, 1874.

Our present improvement consists in combining with the lid of a retort a rock-shaft provided with lifting-toes, and a hinged lever, which is connected to said lid by means of a pin that slides in the end of said lever, in such a manner that when the rock-shaft carrying the lifting-toes is turned in one direction the lid is free to sink down on said guide, and when the lid is brought up to the mouth of the retort and the rock-shaft carrying the lifting-toes is turned in the opposite direction, the lid is raised and its edge is caused to engage with a V-shaped groove formed on a frame, which is secured to the mouth of the retort, and at the same time said lid is forced up tight against the outer surface of the retort. On the rock-shaft are also mounted cams, which serve to depress the lid, so as to disengage it from the V-shaped groove in the frame.

In the drawing, the letter A designates a retort, on the mouth of which is secured a frame or rim, B, the inner edge of which forms a V-shaped groove, a, Fig. 3. C is the lid of the retort, the edge of which is also V-shaped, so that it can be made to engage with the groove a. It must be remarked, however, by referring to Fig. 3, that the bevel of the groove a is different from that of the edge of the lid, so that when said edge is forced into the groove the lid is pressed up against the outer surface of the retort or against the face of the frame B. On the lid C is secured a pin, c, which slides in the end of a lever, D, that swings on a pin, d, se-

cured in a bracket, e, which projects from the side of the retort, the connection being such that when the lid is permitted to follow its inherent gravity it sinks down to the position shown in Fig. 2, and by swinging the lever D outward the mouth of the retort is thrown open.

On the lid C, near its bottom edge, is mounted a rock-shaft, E, which has its bearings in boxes f, and which is turned by a lever, g. On this rock-shaft are secured toes, h, and if the lid is brought to the position shown in Fig. 2, and the rock-shaft E is turned in the proper direction, said toes bear upon arms l, which project from the bottom edge of the retort, and thereby the lid is forced upward and inward, so that its edge catches in the V-shaped groove a, while its inner surface is pressed up tight against the face of the retort or of the frame B. As the lid is raised the pin c slides in the lever D.

On the rock-shaft E are secured cams i i, and if the lid is closed, as shown in Figs. 1 and 3, and the rock-shaft is turned in the direction of the arrow marked near it in Fig. 3, said cams bear against lugs j j, which project from the frame B. If the lid binds or sticks in the groove a, or if it should adhere to the retort, the cams i i serve to release it, and the operation of opening the retort is facilitated.

What we claim as new, and desire to secure by Letters Patent, is—

1. The rock-shaft E, provided with lifting-toes h, in combination with the lid C of a retort, and with the groove a and arms l on the said retort, substantially as set forth.

2. The combination of the swinging lever D, sliding pin c, lid C, retort A, grooved frame B, rock-shaft E, lifting-toes h, and arms l, all constructed and operating substantially as shown and described.

3. The combination of the rock-shaft E and cams i i with the lid C, groove a, and lugs j j, substantially as set forth.

In testimony that we claim the foregoing we have hereunto set our hands and seals this 21st day of October, 1874.

I. HERZOG. [L. S.]
RICHARD KOCH. [L. S.]
